UNITED STATES PATENT OFFICE.

FREDRICK W. CASE, OF LARWILL, INDIANA.

MOLD.

1,219,080.

Specification of Letters Patent. Patented Mar. 13, 1917.

Application filed November 3, 1915. Serial No. 59,478.

To all whom it may concern:

Be it known that I, FREDRICK W. CASE, a citizen of the United States, residing at Larwill, in the county of Whitley, State of Indiana, have invented a new and useful Mold; and I do hereby declare the following to be a full, clear, and exact description of the invention, such as will enable others skilled in the art to which it appertains to make and use the same.

This invention relates to an improved mold, designed primarily for forming curved concrete blocks or the like for cylindrical silos or the like.

It has been found through a considerable experience that the overlapping curved ends 3 and 4 of the side pieces of the mold disclosed in the patent to F. W. Case and W. A. Burnworth, dated August 11, 1914, Patent No. 1,106,625, are invariably springing apart or separated, when tamping the concrete in the mold. Therefore, one of the objects of the present invention is to entirely eliminate said overlapping curved ends 3 and 4 of said patent, and to eliminate the curved piece 5 of said patent, and to otherwise construct the present mold in an improved manner over the mold in said patent, so as to construct or mold a superior and firmer concrete silo block, and one which has more accurate lines of contour.

Another object of the invention is to provide improved means for clamping the opposite sides of the mold securely together.

A further object of the invention is to provide a sheet metal lining for the interior surfaces of the mold.

In practical fields the details of construction may necessitate alterations, falling within the scope of what is claimed.

The invention comprises further features and combination of parts, as hereinafter set forth, shown in the drawings and claimed.

In the drawings:

Figure 1 is a view in perspective of the improved mold constructed in accordance with the invention.

Fig. 2 is a plan view more clearly showing the details of construction.

Fig. 3 is a cross sectional view on line 3-3 of Fig. 1.

Fig. 4 is an enlarged detail view of one of the cam levers to coöperate with the forked end of one of the bars on one side of the mold, to hold the parts of the mold together.

Fig. 5 is a detail perspective view of one of the forked bars which is carried by one of the sides of the mold.

Referring more especially to the drawings, 1 and 2 designate the opposite sides, and 3 and 4 designate the opposite ends of the mold. The inner vertical surface of the end 3 is provided with an elongated rib 5, arched or curved in cross section, but which may be any other suitable shape if desired. The end piece 4 upon its inner face has a vertical longitudinal groove 6, which is designed to correspond with the rib 5, it depending upon what shape the rib 5 is in cross section. The rib 5 and the groove 6 forms a rib on one end of the block and a groove on the other end of the block, so that when a series of blocks are arranged to form the wall of the silo, the groove on one end of each block receives a rib upon the opposite end of an adjacent block, thereby connecting the blocks to prevent their displacement. The end pieces 3 and 4 are hinged at 7 to the outer side piece 1, so that the end pieces will swing outwardly. The leaves 8 of the hinges 7 extend beyond the end pieces 3 and 4, and terminate in reduced extensions 9, to which the cam members 10 are pivoted as at 11, which cam members 10 are provided with levers 12. Bolted to the inner side piece 2 of the mold as at 13 are curved bars 14, the opposite ends of which are forked or bifurcated, as shown at 15. The outer faces of the forks of said bars 14 at the extreme ends of said forks, are provided with bulges 16. When the sides 1 and 2 and the end pieces 3 and 4 are arranged as shown in Figs. 1, 2 and 3, the reduced extensions 9 of the leaves 8 are received between the forks 15 of the bars 14. To permit the forks 15 to receive said reduced extensions 9, the levers 12 are disposed as shown in Figs. 3 and 4, so that the shorter radii, as indicated at a and b of the cam members will pass over and adjacent the bulges 16 of said forks, and then after arranging the parts as disclosed in Figs. 1 and 2, the levers 15 may be thrown to the positions shown in Figs. 1 and 2, thereby causing the surfaces 18 (which are adjacent the longer radii of the cam members) of the cams to cam against and behind the bulges 16 of the forks, thereby holding the sides 1 and 2 and the end pieces 3 and 4 firmly together, in order to receive the concrete or other plastic material, whereby the con-

crete silo block may be formed. Secured to the end pieces 3 and 4 as at 20 are the plates or bars 21, the opposite ends of which overlap the opposite edges of the side pieces 1 and 2, thereby reinforcing or bracing the structure of the mold. The inner faces of the sides 1 and 2 are covered with sheet metal or any other suitable material 22, so as to construct smooth inner and outer faces upon the concrete silo block. The inner faces of the end pieces 3 and 4 are provided with sheet metal face plates 23 to form smooth faces upon the ends of the silo block. In constructing the concrete silo block, the parts of the mold are arranged as disclosed in Figs. 1, 2 and 3, the parts being clamped together securely, after which the concrete or other plastic material is deposited in the mold, afterward tamped thoroughly and firmly into the mold, and afterward the mold may be immediately disassembled, and then set up in another location and refilled, and so on until a wall is completed. However, the concrete may be placed in the mold and allowed to stand for a short period to permit the same to partially set, or allowed to stand for a longer period to permit the concrete to thoroughly set, after which the parts of the mold may be disassembled.

One of the side pieces of the mold, that is, the one which is convexed inwardly, may be removed, by imparting a slight outward movement to one of said end pieces, when the cams 10 are in the positions shown in Fig. 3, disconnecting the forks from the elongated leaves of the hinges, at one end of said side piece, then by imparting a slight reverse transverse movement to said side piece, the forks at the other end of the side piece may be disconnected. The bars 14 may then be disconnected from the removed

side piece, and re-connected to the elongated leaves of the hinges, thereby to hold said end pieces in place, whereby one face of the block may be exposed to the atmosphere, so that the block may thoroughly dry.

The invention having been set forth, what is claimed as new and useful is:—

In a concrete mold, the combination of a side piece curved transversely and two end pieces, of a second side piece curved transversely correspondingly to the first side piece, and between which and the first side piece said end pieces fit with their outer faces flush with the end edges of said side pieces, hinges carried by the first side piece, each having an elongated hinge leaf extending across the end edges of the side pieces and secured to the outer face of an end piece, whereby each end piece may swing outwardly and toward the outer face of the first side piece, whereby the molded block may be easily removed, bars secured to the outer faces of the end pieces and having their ends overlying the end edges of said side pieces, curved bars secured to the outer face of the second side piece and having forked ends extending beyond the end edges of the second side piece to be engaged by the elongated leaves of the hinges, said forks having bulges, and cam members carried by said elongated hinge leaves to coöperate with the bulges, to bind the parts of the mold together in two directions at right angles to each other.

In testimony whereof I have signed my name to this specification in the presence of two subscribing witnesses.

FREDRICK W. CASE.
